(57) **CLAIM**

The ornamental design for a buffing pad with collapsed cell structure, substantially, as shown and described.

DESCRIPTION

FIG. 1 is a top perspective view of a buffing pad with collapsed cell structure showing my new design in accordance to a first embodiment;

FIG. 2 is a top plan view thereof;

FIG. 3 is a bottom plan view thereof;

FIG. 4 is a front elevation view thereof;

FIG. 5 is a side elevation view thereof; and

FIG. 6 is a cross-sectional view thereof taken along line 6-6 in FIG. 2.

FIG. 7 is a top perspective view of a buffing pad with collapsed cell structure showing my new design in accordance to a second embodiment;

FIG. 8 is a top plan view thereof;

FIG. 9 is a bottom plan view thereof;

FIG. 10 is a front elevation view thereof;

FIG. 11 is a side elevation view thereof; and,

FIG. 12 is a cross-sectional view thereof taken along line 12-12 in FIG. 8.

The even broken lines in the drawings illustrate portions of the buffing pad with collapsed cell structure that form no part of the claimed design. The short dash-long dash broken lines in the drawings illustrate boundaries between portions of the buffing pad that form part and do not form part of the claimed design.
